UNITED STATES PATENT OFFICE.

F. B. RICHARDSON AND B. L. RICHARDSON, OF BOSTON, MASSACHUSETTS.

ENEMA-SYRINGE.

Specification of Letters Patent No. 28,196, dated May 8, 1860.

To all whom it may concern:

Be it known that we, FRANCIS B. RICHARDSON and BYRON L. RICHARDSON, of Boston, in the county of Suffolk and State of Massachusetts, have invented an Improved Manufacture of Enema-Syringes; and we do hereby declare that the same is fully described and represented in the following specification and the accompanying drawings, of 10 which—

Figure 1, denotes a side view, and Fig. 2, a longitudinal section of our said syringe, and showing its elastic bulb as arranged at or about at right angles with its tubes of 15 induction and eduction. Fig. 3, is a side view of it with the elastic bulb in line with the tube of induction and at a right angle with the tube of emission. Fig. 4, is a side view of the Davidson syringe wherein the 20 elastic bulb is made with two openings, and arranged with its axis in line with those of the flexible tubes, and is connected to such tubes by two separate metallic tubular connections.

In Figs. 1, 2 and 3, A denotes the elastic bulb or receiver, it being constructed of caoutchouc or other proper elastic material or composition, and with one mouth piece to receive and fit upon one of the three branches 25 x, y, and z, of a three fold metallic connection or coupling, I, whose other two branches are fitted respectively in two long flexible pipes, B, C, one of which, viz, B, is the supply pipe and the other the eduction 30 pipe for such bulb. The longer axis of the bulb is arranged at or about at a right angle with the axis of the eduction tube, and the outer end of the said eduction tube, C, is connected with a valve chamber or case, 35 K, from which either a vaginal, or rectum tube, D, may be made to extend or form a connection piece, d, screwed to the valve chamber. The said valve case we provide 40 with a light elastic ball valve, a, to play toward and away from a seat, b, suitably formed in the valve case.

At the outer end of the supply tube, B, there is another valve case or box, F, terminated by a receiving pipe, G, and furnished with a ball valve, d', to play between a seat, c, and the connection cap, f, of the 50 said valve case. Each valve case is furnished with a tubular projection or tenon, g, to fit into the next adjacent flexible tube and 55 connect it with the valve case.

When the induction tube is inserted in a

mass of fluid and the bulb is seized within and alternately compressed and suffered to expand by the hand of a person, the fluid will be drawn into the bulb and expelled 60 therefrom and through the terminal pipe.

With the ordinary Mattson elastic bulb syringe as constructed with a short metallic induction tube extending below the mouth of the elastic bulb, the operating hand of 65 the person is brought inconveniently over the dish containing the fluid to be injected, and has to perform not only the function of keeping the receiving tube in the dish, but that of operating the bulb, but with our improved syringe, the long flexible induction tube allows its valve box to sink in the fluid and maintain itself under the surface thereof by its own weight. However, the position of the bulb may be varied while being 70 put in operation.

With the enema syringe wherein the elastic bulb is arranged in a line with and connected by separate metallic connections, with two long flexible tubes of induction and 75 eduction (such syringe being exhibited in Fig. 4,) the elastic bulb is also brought into an inconvenient position to be grasped by the hand, as the hand, while operating it, is thrown more or less out of its normal position relatively to the wrist of the arm and consequently, occasions more or less twitching or such a movement of the injection tube as to be inconvenient or often dangerous to the user. With an arrangement of the bulb 80 relatively to the flexible induction pipe, the hand while operating the bulb retains its normal and true position with respect to the forearm, or is not bent at the wrist. Beside this, as we employ but one metallic 85 connection for the bulb and flexible pipes, we save the necessity of having two metallic connections and two mouths to the bulb as employed in the syringe shown in Fig. 4. We employ but three joints in connecting 90 the pipes and bulb, whereas, four are used in the syringe shown in Fig. 4. Therefore 95 the pipes and bulb, whereas, four are used in the syringe shown in Fig. 4. Therefore 100 our syringe is less liable to leakage and derangement.

We are aware, that in the ordinary brass 105 cylinder stomach pump, the cylinder is placed at right angles to the tubes of induction and eduction. This, however belongs to a distinct species of pumping apparatus, or one wherein the fluid is raised into the 110 pump barrel and expelled therefrom by the operation of a piston moving in the barrel,

whereas, our invention relates particularly to such pumps as have an elastic bulb to be held in and operated by one hand of a person and to leave his other hand free to hold 5 the terminal tube.

In that species of pump, to which the stomach pump, and many kinds of metallic lavement apparatus belong, the pump barrel, while the pump is in operation, requires 10 to be held in one hand of the operator while with his other hand he works the piston. Thus, it will be seen, that such pumps require both his hands to be employed in their 15 operation, neither hand being free to hold and direct the terminal tube.

Furthermore, our syringe has an advantage over the Davidson syringe, shown in Fig. 4, inasmuch as with the latter, a large portion of the fluid is likely to remain in 20 the bulb after each compression, and this on account of about half of the bulb being below the line of its pipes, whereas, in our syringe, the whole of the bulb is above the pipes, and being made to stand vertically 25 when in use, it is more favorably situated for a complete discharge of the fluid at each compression of the bulb. Thus, sediment is not so liable to collect in the bulb of our syringe as it is in the Davidson syringe. 30 In our syringe the bulb may be held vertically while in use without creating any sudden bend or flexure of either of its flexible pipes, whereas such is not the case with either the Davidson or the Mattson syringe. 35 Therefore, we lay no claim to the invention of the barrel and piston syringe whether the piston thereof be operated by

the hand of the user or by mechanical and separate means. Nor do we claim either of the elastic bulb syringes of Mattson or 40 Davidson to which reference has hereinbefore been made. Nor do we claim an elastic bulb enema syringe as made not only with a metallic valve case, an elastic bulb placed on such valve case, and a metallic or inflexible 45 terminal tube screwed directly to the valve, but with a flexible induction tube, extending from the valve case, and with the elastic bulb arranged at right angles to the terminal and induction tubes, the whole being as 50 exhibited in the instrument for which a patent was granted May 22nd A. D. 1833 to John Pearshall and David Gilbert. This latter syringe has no flexible eduction pipe, and consequently, as its metallic terminal 55 pipe was attached directly to the bulb, without any flexible connection, the instrument was dangerous in its use, and was abandoned—only one of them having been made as we have been informed by one of the patentees.

What we claim is—

Our improved manufacture of elastic bulb enema syringe as made by combining an elastic bulb, A, two long flexible induction 65 and eduction pipes B, C, and two separate valve chambers K, F, with a three fold separate connector, I, for connecting the elastic bulb and flexible pipes.

FRANCIS B. RICHARDSON.
